UNITED STATES PATENT OFFICE.

RICHARD L. McCREADY, OF ALLEGHENY, PENNSYLVANIA.

MARKING-PEN.

SPECIFICATION forming part of Letters Patent No. 437,312, dated September 30, 1890.

Application filed February 15, 1890. Serial No. 340,600. (No model.)

To all whom it may concern:

Be it known that I, RICHARD L. McCREADY, a citizen of the United States, residing at Allegheny, in the county of Allegheny and State 5 of Pennsylvania, have invented certain new and useful Improvements in a Marking-Pen; and I do hereby declare the following to be a full, clear, and exact description of the invention, such as will enable others skilled in the 10 art to which it pertains to make and use the same, reference being had to the accompanying drawings, which form a part of this specification.

My invention relates to an improved marking or shading pen; and it consists in a tube 15 having a flattened point, slightly beveled, and the said tube adapted to contain a quantity of ink and to flow through an orifice formed in the flat point, as will be fully set forth 20 hereinafter.

In the accompanying drawings, Figure 1 is a plan view of my improved pen or marker, which is constructed in accordance with my invention. Fig. 2 is a side elevation of the 25 same. Fig. 3 is a side view of a blank tube, showing the tapering end before flattening the same. Fig. 4 is an enlarged sectional view of my improved marker, showing the point attached by means of a screw-thread.

To put my invention into practice, I provide a tube *a* of suitable size and length and close the same at one end. At the open end 30 of the tube *a*, I form a screw-thread and at-

tach thereto a tapering circular point *b*, which by suitable means I flatten, as shown in Figs. 35 1 and 2. This point *b* is slightly beveled at *c* (see Fig. 4) in order to enable the operator to hold the marker in an inclined position, and is not entirely closed, but a fine slot or opening *d* extends the entire width of the point. 40

In operation the point *b* is unscrewed from the tube *a* and the same filled with ink. The point is now replaced and the marker ready for use. By holding the implement in an inclined position, so that the bevel surface will 45 be in contact with the article to be marked or written on, and using the same as an ordinary "stub" pen, letters or writing will be formed with heavy shade-lines at the top and bottom.

Having thus described my invention, what I claim, and desire to secure by Letters Patent, is—

The herein-described marking or writing pen, consisting of the tube *a*, closed at one 55 end and provided with a flat tapering point *b*, having an opening *d* the entire width of the said point, and the bevel surface *c*, formed on the said point, substantially as set forth.

In testimony that I claim the foregoing I 60 hereunto affix my signature this 10th day of January, A. D. 1890.

RICHARD L. McCREADY. [L. S.]

In presence of—

M. E. HARRISON,
J. A. HERRON.
